UNITED STATES PATENT OFFICE.

LEWIS E. SPARKS, OF MEMPHIS, TENNESSEE.

GARBAGE-BURNING FURNACE.

1,132,494.

Specification of Letters Patent. Patented Mar. 16, 1915.

Application filed May 8, 1914. Serial No. 837,216.

To all whom it may concern:

Be it known that I, LEWIS E. SPARKS, a citizen of the United States, residing at Memphis, in the county of Shelby and State of Tennessee, have invented new and useful Improvements in Garbage-Burning Furnaces, of which the following is a specification.

This invention relates to improvements in furnaces for burning garbage and similar waste matter and has particular application to a furnace wherein the waste matter will be incinerated and the liquids in the garbage evaporated.

15 In carrying out the present invention, it is my purpose to provide a furnace of the class described which will be constructed in such manner that the draft will circle around the interior of the furnace casing and then 20 pass into the stack thereby raising the temperature within the casing and effectively consuming the garbage therein.

It is also my purpose to provide a furnace of the type set forth wherein the upper surface 25 face of the base will be concaved so as to trap any liquid in the garbage and hold such liquid until the same has been evaporated under the action of the intense heat.

A further object of my invention is to 30 provide a garbage burning furnace wherein the top wall thereof will form a floor or platform to receive the waste matter from the wagons or carts and wherein such floor will be equipped with a discharge opening 35 emptying into the interior of the casing and adapted, when open, to establish communication between the interior of the furnace casing and the upper surface or floor forming face of the top wall thereof so that the 40 waste matter dumped thereon will pass into the casing within the zone of the heat from the fire box.

A still further object of my invention is to 45 provide a furnace of the class set forth wherein the incinerated waste matter may be readily and conveniently removed from the furnace casing in order to facilitate combustion and prevent the covering up of any unconsumed garbage and wherein the fire 50 box may be at all times supplied with the proper fuel to maintain the temperature within the casing.

With the above and other objects in view, the invention consists in the construction, 55 combination and arrangement of parts here-

inafter set forth in and falling within the scope of the claims.

In the accompanying drawings; Figure 1 is a view in front elevation of a garbage burning furnace constructed in accordance 60 with the present invention. Fig. 2 is a horizontal sectional view therethrough. Fig. 3 is a vertical sectional view therethrough. Fig. 4 is a view similar to Fig. 3 taken at right angles to the latter.

Referring now to the drawings in detail, 1 designates a base or bottom wall, while 2 and 3 indicate the front and rear end walls 70 uprising from the base 1, while 4, 4 designate opposite side walls upstanding from the base and coöperating with the front and rear end walls and the base or bottom wall to form a substantially rectangular casing. Closing the upper end of the casing and extending across the latter from side wall to 75 side wall is an arch 5 composed of fire brick or other refractory material and having the opposite longitudinal edges thereof embedded in the side walls and the ends thereof embedded within the front and rear end 80 walls of the casing. Secured to the upper edges of the side and end walls of the casing above the arch 5 and forming, in effect, the top wall of the casing, is a floor or platform 6 upon which the garbage or other waste 85 matter may be dumped from the wagons or carts, while secured to the upper surface of the arch 5 is a covering 7 of heat insulating material, such, for instance, as asbestos 7 and interposed between the covering 7 and 90 floor or platform 6 is a filler 8 of concrete or similar material, the asbestos 7 serving to insulate the arch 5 from the floor 6 so as to prevent heating of the latter in the operation of the furnace.

Uprising from the base or bottom wall 1 within the casing adjacent to the front end walls 2 and to one side of the longitudinal center line of the casing is a stack or flue 9 having the side wall thereof confronting the adjacent side wall 4 of the casing coöperating with the latter to form a fire box 10 equipped with a grate 11 supported by the confronting faces of the walls of the flue and casing and below the grate 11 is formed an 105 ash pit 12. The forward ends of the fire box 10 and ash pit 12 open onto the front end wall of the casing and are closed through the medium of hinged doors 13 and 14 respectively. The base or bottom wall 1 of the 110

casing adjacent to the front end wall and the remaining side wall 4 is equipped with a grate 15, while the front end wall immediately above and below the grate is formed 5 with openings 16 and 17 closed by means of doors 18.

In order that the draft produced by the flue or stack 9 will circle around the casing within the latter so that the temperature of 19 the casing will be raised and the waste matter therein effectively consumed, the side wall of the flue 9 within the casing adjacent to the grate 15 is formed with an opening 19, while the corners at the meeting ends of the 15 side and end walls of the casing are rounded as at 20 and the rear wall of the flue within the casing formed after the fashion of a trapezoid as at 21. In the present instance, the opening 19 in the wall of the flue 9 extends 20 from the bottom wall of the furnace structure to a point approximately centrally of the distance between the top and bottom walls and the remaining portion of the flue wall acts as a baffle for a purpose hereinafter described.

The top wall of the casing or furnace composed of the arch 5, lining 7 and platform 6 is formed, approximately centrally with an inlet opening whereby the garbage 30 and other waste matter may be introduced into the furnace. This opening is provided with a suitable heat resisting lining and closed by means of a cap 21 of suitable construction.

In practice, a fire is built upon the grate 11 of the fire box 10 and fuel fed to such fire by way of the opening controlled by the door 13. The draft produced by the stack or flue 9 causes the heat units to traverse the interior of the casing and owing to the rounded corners 20 at the meeting edges of the side and end walls of the casing and the position of the opening 19 in the base of the flue with respect to the fire box 10, such heat units 45 circle around the interior of the casing thereby raising the temperature of the latter. The cover 21 and baffle plate 26 are now elevated by some suitable mechanism and the garbage and other waste matter introduced 50 into the casing or furnace by way of the opening 22. In the operation of the furnace, the wall of the flue or stack 9 forming one side of the fire box 10 is intensely heated by the burning fuel on the grate 11 so that the 55 inner surface of said wall of the flue opposite the opening 19 is likewise affected and, consequently, the smoke and other gases drawn around the furnace into the opening 19 of the flue impinge against the heated 60 wall of the flue and are effectively burnt up or consumed, thereby rendering the furnace smokeless and enabling all of the gases from the waste matter within the furnace to be consumed. In this instance, the portion of the 65 wall of the flue above the opening 19 acts

as a baffle and is disposed in the path of the gases circling around the furnace so that the force of the gases is broken and the latter directed downwardly into the opening 19 and against the heated wall of the chimney. 70 In the continued operation of the furnace, the gases pass up through the stack 9 and the incinerated waste matter on top of the pile of such matter within the furnace structure is raked onto the grate 15 and the ashes fall 75 through the grate into the pit below the same whence they may be removed by opening the particular door 18, while the unconsumed particles lie upon the grate 15 and in order to consume these particles on the grate 80 15, the door 18 below the grate 15 is opened so that oxygen is fed into the furnace to effectively consume the particles of garbage on the grate 15. Thus, the ashes on the top of the pile may be discharged from the furnace so that the unconsumed matter below such ashes will be subjected to the action of the hot gas passing around the furnace. The garbage or waste within the furnace is preferably raked or agitated frequently so 85 90 as to prevent all residue or ashes from covering up, protecting and smothering the unconsumed particles.

To prevent any liquid which may be in the garbage from draining through the 95 grate 15, the upper surface of the base or bottom wall of the furnace is concaved as at 27 and retains or traps the liquids and holds the latter until evaporated under the action 100 of the heat.

From the foregoing description taken in connection with the accompanying drawings, the construction, mode of operation and manner of employing my improved garbage burning furnace will be readily apparent. It will be seen that I have provided a garbage burning furnace wherein the interior of the furnace is heated to the maximum temperature, the waste matter effectively consumed and the gases carried off 105 and wherein the residue or incinerated matter may be readily and conveniently removed.

While I have herein shown and described one preferred form of my invention by way 110 of illustration, I wish it to be understood that I do not limit or confine myself to the precise details of construction herein described and delineated, as modification and variation may be made within the scope of 115 the claims without departing from the spirit of the invention.

I claim:

1. A garbage burning furnace comprising 120 a base, side and end walls uprising from the base, a top wall co-operating with said side and end walls and said base and formed with an inlet opening whereby the garbage may be introduced into the furnace, a fire box within said furnace adjacent to one side 125 130

wall and opening onto the front end wall thereof, a stack uprising from said base adjacent to said front wall in proximity to one side of said fire box and having the wall 5 thereof adjacent to the fire box within the zone of the heat from the burning fuel in said box, said stack projecting through the top wall and having the side wall thereof remote from the fire box opening into the 10 furnace structure whereby the heat units issuing from the fire box will circle around the interior of the furnace structure to consume the waste matter and gases issuing from such matter, the gases passing through 15 said opening and impinging against the heated wall of said stack.

2. A garbage burning furnace comprising a base, side and end walls uprising from the base, a top wall coöperating with said side 20 and end walls and said base and formed with an inlet opening whereby the garbage may be introduced into the furnace, a fire box within said furnace adjacent to one side wall and opening onto the front end wall 25 thereof, a stack uprising from said base adjacent to said front wall in proximity to one side of said fire box and having the wall thereof adjacent to the fire box within the zone of the heat from the burning fuel in 30 said box, said stack projecting through the top wall and having the side wall thereof remote from the fire box opening into the furnace structure whereby the heat units issuing from the fire box will circle around 35 the interior of the furnace structure to consume the waste matter and gases issuing from such matter, the gases passing through said opening and impinging against the heated wall of said stack, and a grate on 40 said base adjacent to the opening in said stack adapted to receive the ashes from the garbage being consumed, one of the walls of said furnace being provided with a door controlled opening below said grate where- 45 by oxygen may pass through the grate and into said stack through the opening therein and so cause the burning of any unconsumed garbage on said grate.

3. A garbage burning furnace comprising, 50 a base, side and end walls uprising from the base, a top wall coöperating with said side and end walls and said base and formed with an inlet opening whereby the garbage may be introduced into the furnace, a fire 55 box within said furnace adjacent to one side wall and opening onto the front end wall thereof, a stack uprising from said base ad-

jacent to said front wall in proximity to one side of said fire box and having the wall thereof adjacent to the fire box within the 60 zone of the heat from the burning fuel in said box, said stack projecting through the top wall and having the side wall thereof remote from the fire box formed with an opening establishing communication between 65 the stack and the furnace structure whereby the heat units issuing from the fire box will circle around the interior of the furnace structure to consume the waste matter and gases issuing from such matter, the 70 gases passing through said opening and impinging against the heated wall of said stack, said opening extending from the base of the furnace structure to a point approximately centrally of the distance between the 75 base and top wall, the remaining portion of the wall formed with the opening extending into the path of the gases and acting as a deflector to break the gases and direct the latter downwardly into said opening. 80

4. A garbage burning furnace comprising a base, side and end walls uprising from the base, a top wall coöperating with said side and end walls and said base and formed with an inlet opening whereby the garbage 85 may be introduced into the furnace, a fire box within said furnace adjacent to one side wall and opening onto the front end wall thereof, a stack uprising from said base adjacent to said front wall in proximity to one 90 side of said fire box and projecting through the top wall and having the side wall thereof remote from the fire box opening into the furnace structure whereby the heat units issuing from the fire box will circle 95 around the interior of the furnace structure to consume the waste matter and gases issuing from such matter, and a grate on said base adjacent to the open side wall of said stack adapted to receive the ashes from the 100 garbage being consumed, one of the walls of said furnace being provided with a door controlled opening below said grate where- by oxygen may pass through the grate and into the stack through the opening therein 105 and so cause the burning of any unconsumed garbage on said grate.

In testimony whereof I affix my signature in presence of two witnesses.
